UNITED STATES PATENT OFFICE

THOMAS H. BANFIELD, OF PORTLAND, OREGON

DOORCHECK

Application filed July 21, 1931. Serial No. 552,205.

This invention relates generally to door checks, and particularly to devices for controlling trap doors.

The main object of this invention is to provide a door check which will retard the closing action of trap doors and assist in the opening action, and which will incorporate a means whereby the action of the spring element may be easily and accurately adjusted.

10 The second object is to construct a door check which will be easy to manufacture and assemble and which will have incorporated therein a locking device for the tensioning means.

15 These, and other objects, will become more apparent from the specification following as illustrated in the accompanying drawings, in which:

20 Fig. 1 is a transverse section through the trap door.

Fig. 2 is a plan of the device.

Fig. 3 is a view of the locking mechanism in an unlocked position.

25 Fig. 4 is a view similar to Fig. 3 but showing the parts in a locked position.

Fig. 5 is a section taken along the line 5—5 in Fig. 2.

Fig. 6 is an elevation of the device showing the handle and base broken away in section.

30 Fig. 7 is a section taken along the line 7—7 in Fig. 6.

Fig. 8 is a section taken along the line 8—8 in Fig. 5.

35 Similar numbers of reference refer to similar parts throughout the several views.

Referring in detail to the drawings, there is shown in section a sidewalk 10 having an opening 11 around the inner and upper edges of which is secured a frame 12 in which is incorporated a channel 13 which is employed for drainage purposes.

40 On opposite sides of the opening 11 are the hinged mountings 14 for the trap doors 15 such as are in common use. The trap doors 15 are usually made of metal of sufficient thickness to withstand the loads which may be imposed thereon. This requires that even the ordinary size of opening must have a door of considerable weight, and it is to facilitate the opening and closing thereof that this de-

vice has been constructed, as well as to prevent the destruction of the doors by the closing of same in a violent manner. Transverse braces 16 are required on the under side of the doors 15 for stiffening purposes.

45 Turning now to my invention same will be seen to consist of a round shaft 17 whose ends 18 turn down and journal in the bushings 19, one of which is carried in a standard 20 welded against the frame 21 and the other 22 of which is carried in the standard 22 which is secured to the frame 21 by the bolts 23.

55 On the shaft 17 is formed a ratchet wheel 24 on one side of which are formed the teeth 25 of a jaw clutch adapted to engage similar teeth 26 formed on the hub 27 of an arm 28 whose outer end carries a roller 29 which rides against the under side of the door 15. Pivot-
ed on the side of the arm 28 is a lock 30 which
60 is mounted freely on the bolt 31 and is pro-
vided with an extension end 32, by means of
which it is operated. The lock 30 has a slot
65 33 formed therein on an arc struck from the
center of the bolt 31 and of a width sufficient
to receive the portion 34 of the shaft 17. A
70 washer 35 is placed between the portion 34 of
the shaft 17 and the bushing 19.

75 A torsion spring 36 is mounted on the shaft
17 and its end 37 passes through the standard
22, while its end 38 occupies a recess in the
ratchet 24.

80 On the frame 21 is mounted a latch 39 which
is in the form of a right angle whose corner
40 can swing into position between the teeth
41 of the ratchet 24 (as shown in Fig. 7). The
85 latch 39 is pivotally mounted on the screw 41
and its projecting end 42 engages a spring 43
which is held by the screws 44 and 45. The
screw 45 also forms a stop for the latch 39
when in an unlocked position (as shown in
90 Fig. 3). The function of the spring 43 is to
urge the latch 39 to either a latched or an
unlatched position.

95 The operation of the device is as follows:
When desiring to increase the torsion of the
spring 36 it is necessary to move the arm 28 to
the position shown in full lines in Fig. 8, in
which it will be possible to swing the lock 30
out of engagement with the portion 34 making
it possible to slide the arm 28 endwise and
100

disengage the teeth 25 and 26. If any torsion exists in the spring 36 it will be necessary to move the latch 39 into position before disengaging the teeth 25 and 26.

- 5 The arm 28 is now rocked in the proper direction, after which the teeth 25 and 26 are again engaged and additional torsion given the spring 36 by swinging the arm 28. This operation can be repeated or reversed as often 10 as desired until the required spring action is obtained.

While it is necessary to position the latch 39 manually, it is unlatched automatically by a movement of the arm 28.

- 15 It can thus be seen that this door check, while being simple to manufacture is easy to assemble and adjust to suit the requirements of the particular installation involved.

Attention is drawn to my United States 20 Patent Number 1,801,840, over which this is an improvement.

I claim:

- 25 1. A check for trap doors consisting of a pair of standards, a shaft journaling between said standards, said shaft having a ratchet wheel thereon, a rockable arm rotatably mounted on said shaft, a jaw clutch between said rockable arm and shaft, means for preventing the disengagement of said jaw clutch 30 when said arm is in a raised position, a torsion spring for urging said ratchet in one direction of travel, and a latch cooperating with said ratchet.

- 35 2. A door check having in combination a pair of spaced standards, a shaft journaling in said standards, a ratchet wheel on said shaft, a torsion spring between said ratchet wheel and a standard, a manually set latch which may be brought into engagement with 40 said ratchet teeth to resist an unwinding action of said spring, a door-operating arm mounted on said shaft, a jaw clutch between said arm and ratchet, and a lock for said jaw clutch adapted to prevent the disengagement 45 thereof except when said arm is in a door-closing position.

THOMAS H. BANFIELD.
